UNITED STATES PATENT OFFICE.

LAWRENCE SKOK, OF CLEVELAND, OHIO, ASSIGNOR, BY MESNE ASSIGNMENTS, TO
ALBERT E. HODGINS, OF CLEVELAND, OHIO.

METAL CASING FOR LEAF SPRINGS.

Application filed April 12, 1922. Serial No. 551,773.

To all whom it may concern:

Be it known that I, LAWRENCE SKOK, a citizen of the United States, residing at Cleveland, in the county of Cuyahoga and State of Ohio, have invented a certain new and useful Improvement in Metal Casings for Leaf Springs, of which the following is a full, clear, and exact description, reference being had to the accompanying drawings.

This invention relates to lubricating apparatus, and is concerned with improvements in metal lubricator casings for vehicle springs of the semi-elliptic type.

The object of my invention is the provision of an oil proof casing adapted to cover the spring laminations and having a metal or armored reinforced casing comprising a series of articulated metallic sections embracing a fabric jacket surrounding the spring laminations.

More specifically, my invention is concerned with an improved metallic casing having the general characteristics of the spring casing described and claimed in my Patent No. 1,284,482, issued November 12th, 1918, but embodying a novel construction of the respective articulated elements of the casing which permits of its being cheaply manufactured and adapted to completely enclose a fabric lining in a dust and lubricant tight manner while being capable of ready application to the spring.

Other objects will be hereinafter set forth in the following description taken in connection with the accompanying drawings, which illustrate a preferred embodiment of my invention. The essential features will be summarized in the claims.

In the drawings, Fig. 1 illustrates the device as applied to a quarter elliptic spring; Fig. 2 is a perspective view of one of the top elements which comprise the metallic casing; Fig. 3 is a similar view of one of the bottom elements; Fig. 4 is a plan section taken substantially along the line 4-4 of Fig. 1 showing the construction of the connections between the respective elements; Fig. 5 is a transverse section taken through the casing and spring laminations and illustrating the manner of attaching

the lubricating nipple to the casing; Fig. 6 is an enlarged fragmentary illustration of one of the joints between the respective casing elements; Fig. 7 is an alternate pivotal construction.

In accordance with the object of my invention, I have arranged a casing having an impervious one piece fabric lining 9, completely surrounding the spring laminations and cut in such a manner from a fabric sheet that it may be neatly folded around the respective spring leaves with an overlapping seam, as illustrated at 10 in Fig. 5. This lining may preferably be wrapped around the spring leaves with the lap extending longitudinally of the top spring blade 11.

A series of U-shaped metallic members hereinafter designated by reference characters 12, 13, 14, 15, 16, 17 and 18 are positioned to engage the lining with the top portions thereof in juxtaposition with the overlapped portions of the lining while their side portions may extend downwardly and over the sides of the spring leaves. A similarly formed set of bottom members are provided which are adapted to engage the bottom surface of the lining. These bottom casing members may have pivotally connected side portions 19, which are assembled in overlapping relation with the downwardly extending portions 20.

The side portions of the members have suitable perforations 21 and 22, formed therein for the purpose of articulately securing the respective members together. Surrounding these perforations, I have provided depressed annular portions which serve to increase the efficiency of the joint formed between the cover members in a manner to be presently described.

The side flanges of the respective elements of the casing decrease in size from the middle portion A to the outer turned-up end portion B of the upper spring leaf, as illustrated in Fig. 1. The perforations 21 and 22 in each succeeding set of elements are formed therein to approximately lie in an arcuate median line relative to the sides of the casing members and extending from the spring support to the outer end of the

spring, thus permitting a deflecting of the spring while at the same time maintaining the articulated members in close engagement, irrespective to the amount of deflection in the spring.

The provision of a simple efficient joint construction which will permit of a ready assemblage of the respective elements is important in that it is highly desirable to have 10 uniformity in the appearance of the casing, as well as to avoid the use of protruding pins, lugs or other expedients which would prevent easy cleaning of the casing. I accordingly prefer to use soft metal eyelets as 15 pivot members which may be readily inserted in the perforations of the casing members when the latter are being positioned on the spring.

It will be noted from Fig. 4 that the annular upset portions surrounding the perforations in the top and bottom members are maintained in intimate contact with the corresponding upset portions formed in the adjacent members by eyelet rivet members 25 20 and 26, thus permitting a relatively free movement of each set of top and bottom members with the adjacent joined members.

The diameters of the upset portions of the bottom members may be of sufficient size to 30 provide a nesting zone for the interiorly disposed heads 25^a and 26^a of the rivet members 25 and 26, respectively, thus presenting a smooth interior casing surface in contact with the fabric lining. The size of the upset engaging portions of the overlapping flange members may be progressively increased from the inner to the outer flanges to provide a free movement therebetween and at the same time serve to strengthen the 40 pivot connection to the casing elements. Furthermore, the upset portions of the bottom members may be sufficiently large to permit the use of a hollow rivet, such as is illustrated in Fig. 6, which may be provided 45 with a substantial head, as shown at 25^a and 26^a. Hence when the outer end thereof is deformed in the manner illustrated by the dot and dash lines in Fig. 6 the pressure exerted upon the rivet during the assembling 50 operations will not cause the head thereof to damage the fabric lining.

If desired, a screw member 28 engaging an interiorly disposed washer member 29 may be used in place of the eyelet 25, in 55 which instance the washer 29 may have a tapered perimeter adapted to engage the perimeter of the depressed portion formed in the flanges of the bottom members, as shown in Fig. 7. Any suitable means, such 60 as soldering the head of the screw member to the flange of the top member, may be used to prevent the displacing of the screw when once assembled on the casing.

To fill the interior of the casing with lubricant, I have provided a lubricating nip-

ple 30, as shown in Fig. 5, secured to an inner threaded washer member 31 having an annular flanged portion of considerably less thickness than the threaded portion which may bear against the fabric lining while the 70 flat side of the washer may rest in contact with the side edges of the spring laminations. An exteriorly disposed washer member 32 may engage a shoulder formed on the lubricating nipple and serve as a means to 75 clamp the fabric jacket and the side flanges of an upper and lower member comprising one of the articulated units. A leak-proof connection is thus provided, whereby the 80 lubricating gun may be connected to the interior of the casing and the lubricant forced therefrom throughout the length of the casing and between the spring laminations under considerable pressure.

The end of the casing may be suitably sealed by clamp members, if desired, or the respective units comprising the end section thereof may be arranged to press the fabric jacket into intimate contact with the surfaces of the spring leaves.

It is to be seen that I have provided a casing for a leaf spring built up of a number of articulated units, each unit comprising an upper and a lower U-shaped unit member having the flanges thereof joined, 95 whereby the upper and lower members have no relative movement but are pivotally joined to the adjacent units in overlapping relation whence no interference is offered to the deflecting movements of the spring 100 leaves.

Furthermore, the nature of the construction is such that the fabric lining surrounding the spring blades is reinforced by an armour in such a manner that lubricant may 105 be forced into the fabric jacket under sufficient pressure to insure lubrication between the spring leaves throughout the length thereof. Furthermore, the construction of the connection of the respective units is of such a simple character that the respective members comprising the casing may be rapidly and easily assembled upon the spring 110 consequent to the placing of the fabric lining about the spring leaves. Furthermore, if an eyelet is used as the pivotal member in joining the respective members, the casing may be easily removed from the spring in case of emergency, such as the replacing of 115 a broken leaf, by filing away the heads of the rivets without damaging in any manner the elements of the casing.

Having thus described my invention, I claim:

1. A casing member for a laminated 125 spring comprising an inner lubricant retaining fabric jacket and an outer metallic reinforcing jacket formed of a series of members embracing the top and sides of the spring, each member being positioned on the 130

spring in overlapping relation with the adjacent top members, and a second series of members embracing the bottom and sides of the spring, said upper and lower members 5 being oppositely disposed on the spring with the sides thereof in overlapping relation with the sides of the top members, whereby they may be joined on each side of the spring by pivot members extending through 10 the sides of the superposed top and bottom members and through overlapping side portions of adjacent members.

2. A casing member for a laminated spring comprising an inner fabric jacket 15 and a series of relatively movable U-shaped members embracing the top and sides of the spring and extending longitudinally thereof, said U-shaped members being positioned on the spring with the ends thereof in overlapping relation, joining means comprising a pivotal connection formed in the overlapping side portions of the respective members, and a series of similarly formed U-shaped members positioned to embrace the 20 bottom and sides of the spring, the side flanges of said bottom U-shaped members being in overlapping relation with corresponding members comprising the top of the casing and joined thereto by the same 25 pivotal constructions which join the respective top members.

3. A casing member for a laminated spring comprising a series of articulated box-like units, each unit comprising an upper flanged member and a lower flanged member having the respective flanges 30 thereof assembled on the spring in an overlapping relation adjacent the sides of the spring, and having the end portions thereof 35 in overlapping relation with adjacent units, and securing means extending through overlapping portions of the units comprising

transverse pivotal connections, whereby the respective units are relatively movable.

4. In a casing for laminated springs, the 45 combination of a lubricant impervious fabric material completely surrounding the spring laminations, a series of articulated members formed to embrace the bottom and sides of said fabric lining, and a second 50 series of articulated members formed to embrace the top portion of the lining and the side portions of corresponding bottom members, and coupling means affording communication to the interior of the lining whereby 55 a grease gun may be connected thereto to force lubricant throughout the length of the casing and between the respective spring laminations under relatively high pressure, the top and bottom members having pivotal 60 connections adjacent the sides of said spring laminations, whereby a double side wall construction of unusual strength may be obtained to resist the internal pressure of the lubricant when the casing follows the deflections of the spring.

5. In a spring casing of the character described, the combination of a fabric lining completely surrounding the spring laminations, and a series of articulated units comprising a lower member embracing the bottom and sides of the lining and an upper member embracing the top portion of the lining and the side portions of said bottom member, whereby a metallic armor is provided for the lining which completely surrounds the respective portions of the lining, said members being held in relative position during flexing of the spring by pivot members extending through the side walls of the 70 75 respective members.

In testimony whereof, I hereunto affix my signature.

LAWRENCE SKOK.
